MANUFACTURE OF BOBBIN SPUN RAYON

Arthur L. Jackson, West Asheville, N. C., assignor
to American Enka Corporation, Enka, N. C., a
corporation of Delaware

Application June 12, 1941, Serial No. 397,793

15 Claims. (Cl. 242—43)

This invention relates to the manufacture of threads of synthetic origin, and is more particularly directed to an improved method and apparatus for the bobbin spinning of rayon.

Although bobbin spinning is one of the older systems for the manufacture of rayon, it persists as the leading commercial method. This is unquestionably due to the basic simplicity and versatility of the process, as well as to the superior quality of yarn produced thereby.

Essentially, bobbin spinning consists in the collection of freshly spun thread upon a foraminated bobbin and the after-treatment of the bobbin-supported wound body. Necessarily, bobbin spinning is intermittent, for a spinning machine must be doffed upon the completion of the simultaneous preparation of a large number of thread packages; and, since each doffing requires concomitantly the replacement of the filled bobbins by empty ones and the threading up of each unit of the machine, it is inherently advantageous to wind packages of as great weight as possible consistent with satisfactory after-treatment. Furthermore, since each bobbin undergoes the same amount of manipulation during after-treatment, it is in the interest of operating economy to treat as much thread as possible on a single bobbin during each such operation.

Previous efforts to attain the foregoing advantages have, in general, followed two lines. One of these involves the use of larger spools and the other is concerned with the winding pattern of the thread.

The employment of large spools has not resulted in a solution of the basic problem of bobbin spinning for, although it is obvious that a bobbin of large size will hold more thread than a small one, there are limits beyond which increases in bobbin size are no longer feasible. These limits are imposed by the structure of various units on which the thread is treated as well as by the structure of twisting machines on which the spinning bobbins are customarily placed upon completion of after-treatment. Then, too, during spinning, mechanical difficulties are encountered if the length of the bobbin is too great, the bobbins being customarily supported from one end only and the thread being laid up thereon generally according to a pattern controlled by a reciprocating traverse bar. Thus, the optimum bobbin size is now fairly well stabilized in the rayon industry and recent efforts directed to the production of washable thread packages of in-

creased weight have been directed to control of the winding operations.

The winding pattern schemes heretofore proposed in the interest of producing heavier packages of rayon thread susceptible to satisfactory after-treatment have not met with commercial success, although some improvement in the washing qualities of smaller packages has resulted. Usually, pattern control systems involve a cam-directed traverse bar, the purpose of which is to control the manner in which successive layers of thread are laid up on the spinning bobbin. In theory, there have been several patterns suggested which should result in the production of large packages of satisfactory size. In practice, however, this has not been the case, the packages produced being characterized by non-uniform permeability. This non-uniformity may take a number of forms. Thus, thread packages are frequently characterized by areas too dense to be washed at all, while others may be washed, but, because of differences in thickness along various radii of the packages, each after-treatment must be continued for a period of time sufficient to properly wash the portions of greatest radial thickness, with resultant inefficient waste of washing time as regards the portions of lesser thickness. The consequence of these difficulties is, therefore, either thread not uniformly after-treated and hence inferior in quality, or properly after-treated thread more costly to produce than that wound into light-weight packages. So it is that the industry has been heretofore forced to forego the economy inherent in the preparation of thread packages of substantial weight.

It is, therefore, an object of this invention to overcome all of the foregoing difficulties and to provide a process and apparatus for the preparation of wound packages of freshly spun thread of synthetic origin characterized by uniform permeability and density and a weight greatly in excess of that heretofore attainable.

According to this invention, it is contemplated that thread be laid up in package form by apparatus so controlled as to accurately reproduce a theoretically desirable pattern.

It is within the purview of this invention to greatly increase the winding periods in the manufacture of bobbin spun rayon while, at the same time, improving the quality of the thread produced.

Other objects and advantages of this invention will be apparent upon consideration of the following detailed description of a preferred em-

bodiment thereof in conjunction with the annexed drawings wherein:

Figure 1 is a view in side elevation of a portion of a bobbin spinning machine incorporating a winding control apparatus constructed according to the present invention;

Figure 2 is a view in section taken along the line 2-2 of Figure 1;

Figure 3 is a view in section taken along the line 3-3 of Figure 1;

Figure 4 is a detail view taken along the line 4-4 of Figure 1;

Figure 5 is a view in section taken along the line 5-5 of Figure 2; and

Figure 6 illustrates a completed thread package according to the present invention, broken away at one end to show the first several layers of thread on the package.

The illustrated apparatus consists of a plurality of driven foraminated collecting bobbins 10 onto each of which a thread issuing from a spinning bath, not shown, is wound. The thread is laid up on each package by a thread guide 11, these guides being attached to and carried by a traverse bar 12. Traverse bar 12 underlies and reciprocates axially of bobbins 10, the movement thereof being initiated by a cam 13 and controlled as to length of stroke by a stroke shortening mechanism designated generally by the numeral 14.

It will be seen that each of the bobbins 10 is mounted on a bobbin holder 15 which is provided with a drive shaft 16 mounted in bearings 17 and 18 suitably attached to portions of the frame 19 of the machine. Each drive shaft 16 is provided with a drive gear 20 meshing with and driven by a gear 21. The gears 21, corresponding in number to the number of bobbins with which the machine is provided, are keyed at spaced points along a shaft mounted for rotation in bearings 23 and 24 supported by portions of frame 19. Shaft 22 constitutes the main drive shaft of the spinning machine, rotation being imparted thereto through gear 25 driven from any suitable source, not shown. It is, of course, contemplated that said suitable power source may operate through a variable speed transmission so that the rotational speed of bobbins 10 will be progressively decreased during the winding period to an extent sufficient to compensate for a tendency toward increased take-up speed brought about by increase in the effective diameter of the bobbin because of the body of thread built thereon. Such variable speed transmissions for maintaining a constant bobbin take-up speed are per se known and form no part of this invention. An example of such an arrangement is shown and described in Patent 2,159,032 to W. G. Lea. It is apparent, therefore, that when shaft 22 is driven each of the bobbins 10 is caused to rotate and, since all gears 21 and 20 are the same size, the speed of rotation of each bobbin 10 will be equal to that of all other bobbins with which the machine is provided.

Upon reference to Figures 1 and 2, it will be noted that, in addition to gears 21 and gear 25, shaft 22 is likewise provided with a gear 26 the purpose of which is to drive cam 13. The movement of cam 13 is effected through a speed reduction gear train consisting of gears 27, 28, 29, 30, 31 and 31a. Gears 21 and 28 are keyed adjacent opposite ends of a shaft 32 mounted in bearings 33 and 34. Gear 27 meshes with gear 26 and through shaft 32 drives gear 28. Gears 29 and 30 are mounted on stub shaft 35, gear 75

20 meshing with gear 28 and gear 30 serving to drive gear 31 of larger diameter. Gear 31 is mounted on a shaft 36 and meshes with gear 31a mounted on shaft 37.

5 The shaft 31, in addition to supporting gear 31a, likewise supports cam 13, the hub 38 of which is keyed thereto for rotation therewith. Inasmuch as shaft 31 must support cam 13 as well as gear 31a, bearings 39, 40, 41 and 42 are 10 provided, their design being such as to insure proper absorption of axial as well as radial thrust.

It is now apparent that cam 13, although driven from shaft 22 which drives the bobbins 10, will 15 rotate at a far slower speed than said bobbins. Thus, since the speed of rotation of cam 13 controls the speed of reciprocation of traverse bar 12, while the speed of the bobbins 10 controls the linear speed of take-up, the thread will be wound on said bobbins in the form of a helix, the angle of which at the beginning of the spinning period, primarily depends upon the ratio of cam speed to bobbin speed. It is equally evident, however, that to insure the production of a truly helical wind by the synchronization of the rotation of cam 13 and bobbins 10, the former must develop along a straight line, i. e., the linear movement of its follower must always be directly proportional to the angular displacement of the 20 cam throughout its rotation. In this way, the cam imparts to its follower a reciprocating motion of substantially unvarying characteristics or, in other words, between reversals of direction at any given time, the follower will move at a constant speed. To this end, cam 13 is provided 25 with a groove, so cut as to insure movement of its follower 43 in a linear sense in direct proportion to the angular displacement of cam 13 in its rotation with shaft 31. The movement of the follower is transmitted unimpaired to the traverse bar by apparatus to be hereinafter described.

Cam follower 43 is supported in a cross head 44 provided with apertures for the reception of rods 45 and 46 on which the cross head may freely 30 reciprocate while at all times being confined to movement in a single plane. Rods 45 and 46 are rigidly held in spaced sleeves of a pair of brackets 47 and 48 which are attached to vertical portions of frame 19.

35 An arm 49 is pivotally attached to cam follower 43 at one of its ends while, at its other end, it is pivotally attached to a nut 50. In this regard, note Figures 1, 3 and 5 in which it can be seen that arm 49 is a double one and that pins 50a and 50b connect the free ends thereof to nut 50.

40 Nut 50 is arranged to slide vertically in a curved double trackway 51 which constitutes an integral portion of stroke shortening device 14. Device 45 51 is attached, at its end remote from the location of nut 50, to a rock shaft 52 mounted in bearings 53 and 54 atop frame 19. Depending from rock shaft 52 are arms 55 and 56 which support 50 traverse bar 12. The support of traverse bar 12 is not direct, however, as may be seen in Figure 2. At the ends of arms 55 and 56 remote from the ends keyed to shaft 52 they are pivotally attached to horizontally extending links 57 and 58 which in turn are pivotally attached at their other ends to depending arms 59, only one of which can be seen in Figure 2. Arms 59 are pivotally attached to a rock shaft 60 and serve to duplicate the movement of arms 55 and 56 on the opposite side of the machine. Thus, in the interest of operating economy the left side of the spinning machine as

viewed in Figure 2 may also be provided with a series of bobbins and the laying up of thread thereon can be controlled by cam 13. Because the links 57 and 58 are pivoted to the depending arms 55, 56 and 59, the reciprocating motion ultimately transmitted to thread guide 11 will be in a single moving horizontal plane thus preventing the guides from tilting in passing from one end to the other on the spools.

Depending from links 57 and 58 are traverse bar supporting members 61 and 62. Thus, when cam 13 is rotated, follower 43 reciprocates causing oscillation of shaft 52 through rocking stroke shortening device 14. Oscillation of shaft 52, of course, causes reciprocation of traverse bar 12. It should be noted that, although stroke shortening device 14 is susceptible to simple harmonic motion, the nut 50 is so remote from shaft 52 as to maintain and transmit substantially unimpaired the movement of the cam follower. Since it is desirable that the ends of wound packages of rayon be conical in form, however, the cam follower movement must not only be maintained but stroke shortening must be superimposed thereon in a manner to insure continuous movement of the traverse bar 12, between changes in direction, at a speed directly proportional to the angular displacement of the cam. Otherwise, the formation of a series of superimposed oppositely directed true helices upon the bobbin cannot occur.

To insure stroke shortening, without interference with the transmission of cam development to traverse bar 12, is the purpose of stroke shortening device 14. Device 14 consists of two parallel frame members 63 and 64 attached to and depending from a sleeve 65 which rotates with shaft 52. Between the two members 63 and 64 a ratchet wheel 66 is mounted for rotation on a shaft 67, this shaft also having pivoted thereto the bifurcated end of an arm 68 which is normally maintained in a fixed position by a spring 69. Spring 69 serves to bias arm 68 against a stop member 68a of any conventional type. Pivoted between the shanks of the bifurcated portion of arm 68 is a pawl 70 maintained in engagement with the teeth of ratchet wheel 66 by a spring 71. The end of arm 68 remote from the point of attachment to shaft 67 is arranged to contact a roller 72 depending from the top of frame 19. Thus, as the entire stroke shortening assembly 14 is rocked by arm 49 each cycle of movement will be accompanied by the striking of arm 68 against roller 72 to cause said arm to move in a clockwise direction as viewed in Figure 3 thereby driving ratchet wheel 66 in the direction of the arrow through the medium of pawl 70. As spring 69 returns arm 68 to normal position when said arm and roller 72 are out of contact, a pawl 73 maintains ratchet wheel 66 in position. Another ratchet wheel 76 is mounted on a shaft 74 parallel but below shaft 67. Also mounted on shaft 74 is a driving pawl 75 including a pivoted tooth normally maintained in engagement with ratchet wheel 76 by a spring 77. Pawl 75 is adapted to be successively engaged by each of the four pins 78 with which ratchet wheel 66 is provided. These pins cause movement of pawl 75 in a counterclockwise direction as viewed in Figure 3, and such movement is transmitted to ratchet wheel 76. The return of pawl 75 is effected by spring 79 attached to a portion of its shank which extends below the pivot point about shaft 74. Ratchet wheel 76, being keyed to shaft 74, serves to drive a gear

80 also attached thereto. Gear 80 meshes with a gear 81 mounted on a shaft 82 parallel but below shaft 74. On this shaft a bevel gear 83 is also mounted. Bevel gear 83 meshes with bevel gear 84 which is affixed to one end of a threaded shaft 85 upon which nut 50 is threaded. Intermediate shafts 14 and 82 a rod is provided extending from frame member 63 to frame member 64. This rod serves to anchor spring 79 acting on pawl 75 as well as a spring 86 acting on the shank of pawl 73 and spring 87 acting on a pawl 88 which serves to hold ratchet wheel 76 against undesired rotation during the return of pawl 75. Pawl 88 is mounted for free rotation about shaft 82.

From the foregoing, it will be seen that the extent of rotation of screw 85 during any spinning period will depend upon the number of oscillation cycles of stroke shortening mechanism 14 which in turn will depend upon the number of revolutions of cam 13. It can be further seen that rotation of screw 85 will vary the distance of nut 50 from shaft 52 and thus vary the amplitude of the rocking movement of the latter to an extent varying with the distance of the nut therefrom. For this reason screw 85 is arranged to be driven in such a way as to cause nut 50 to gradually move away from the rock shaft 52 during the spinning period, the movement, by virtue of the speed reduction pawl drive, being so gradual that its completion will coincide with the completion of the winding of packages of the desired size on bobbins 10. The effect of the shortening of the amplitude of rocking movement of shaft 52 is to reduce the length of the path of travel of traverse bar 12 thereby producing packages having conical ends. Despite the shortening of the stroke of the traverse bar, it will be seen that its movement will remain directly proportional to the linear displacement of the cam. Thus, the packages between the conical ends will be of uniform cross-section. Necessarily, of course, stroke shortening will reduce the speed of travel of the traverse bar between reversals of direction for any given frequency, but the actual speed of travel of the traverse bar between reversals of direction, at any one time, will be directly controlled by the speed of rotation of the cam. The phenomenon just mentioned is evidenced in the package by a progressively closer spacing of truly helical coils of thread during the winding period. The result of this is a controlled pattern wind of maximum uniform density consistent with good washing characteristics.

At the close of the spinning period, it will be recognized that nut 50 will be located a maximum distance away from rock shaft 52. As a consequence, the motion of screw 85 must be reversed and nut 50 returned to starting position before the beginning of the next spinning period. This return is effected by manual operation of a crank 89 attached to and carried by shaft 82 of stroke shortening mechanism 14. Through crank 89 shaft 82 is rotated in the direction opposite to that in which it is driven through gear 81. Pawls 88 and 75 are provided with pins 88a and 75a, respectively, which are held down by hand to allow ratchet wheel 76 to turn freely during this operation. Note that pawl 88, being freely rotatable about shaft 82, is not driven during reversal of screw 85 to return nut 50 to starting position.

It has now been shown that the production of a satisfactory winding control movement of

the traverse can be effected by the use of a cam of straight line development and that stroke shortening may be superimposed upon the pattern without distortion of its character. It is further necessary, however, that the thread laid up on the bobbins exactly follow the pattern of movement of the traverse bar. To this end, a novel type of thread guide has been devised.

Referring again to traverse bar 12, it will be seen that said bar is provided with a plurality of raised portions 90 underlying and in the same vertical plane as the various bobbins 10. A rod 91 is passed through each of the raised portions 90 and a hub 92 is pivoted thereto. Extending upwardly from each hub 92 is a fork 93 the tines of which are adapted to contact tangentially the respective bobbin. In order to insure firm contact and at the same time to allow for increases in package diameter during winding, a counter-weight extends from each hub 92 at a point diametrically opposite fork 93. The distance of the weight from the axis may be made adjustable to insure proper contact consistent with avoidance of injury to threads having different characteristics as regards resistance to abrasion. Because of the fact that the tines of each forked guide 93 actually contact the bobbin and the coils of thread wound thereon, there can be no lag between the movement of the traverse bar and the thread directed thereby. Thus, the thread will follow accurately the pattern of movement of traverse bar 12 even during changes of direction, the break being sharp to insure avoidance of humps at the end of the package.

A plurality of self-threading guides 95, see Figure 4, are attached to traverse bar 12, at spaced points along its length coinciding with the points of location of packages contacting thread guides 11. The self-threading guides 95 are provided with a slot at 96 arranged below and in registry with the slot defined by the tines 93 of thread guides 11. Thus, in threading up, the pull between the thread source and the collecting bobbin will cause the thread to slide along the right-hand surface of guide 95, as viewed in Figure 4, thus pulling the thread into the slot at 96. Guide 95 is provided with an extension 97 received in a socket in traverse bar 12, the extension serving to lock the guide in position. A pin 98 constitutes the primary support for guide 95, said pin passing through the traverse bar as can be seen in Figure 2.

By the use of the foregoing apparatus, heavy wound packages of thread may be produced, the packages being characterized by uniform permeability and uniform radial thickness, except at the conical ends. It is evident that because cam 13 and bobbins 10 are each driven from shaft 22 they are driven in synchronism. The linear movement of the follower associated with cam 13 is directly proportional to the angular displacement of said cam. The consequence of this is the production of truly helical coils throughout the entire winding period. As the coils are superimposed, the angles of succeeding helices will be reduced due to the shortened travel of the traverse bar; but, at all points in its path of travel between reversals of movement, traverse bar 12 will move at a constant speed. There is no acceleration or deceleration thereof between reversals of movement which will cause localized close coil spacing evidenced in the final package by humps and valleys, the former requiring a longer washing period. The winding path being so accurately controlled allows for very close

winding with uniform interstices throughout the package which permit the passage of washing liquid therethrough. The interstices are not continuous, however, in a radial sense, so that all portions of the thread are properly treated during the washing operation.

It is an important phase of this invention that the stroke shortening device 14 does not interfere with the transmittal of the cam development to the traverse bar. The importance of this is emphasized when it is borne in mind that the prior art constructions are characterized by a stroke shortening effected by alteration of the axis of the cam with incident interference with the development thereof or by divorced stroke shortening means having a movement such as to interfere with the cam development.

Having now described the invention in its preferred form, it is understood that variations and modifications may be made therein without departing from the spirit of the invention, and it is desired that the scope thereof be limited only by the spirit of the appended claims.

What is claimed is:

25. 1. A method for the preparation of heavy packages of freshly spun thread of synthetic origin which comprises, supplying for collection thread moving at a substantially uniform linear speed, forming such thread as supplied into a plurality of superimposed oppositely directed substantially true helices, traversing the thread across the face of the said package at a constant speed between reversals of direction at any given time and from a point in contact with the surface 30 of the package, and regularly progressively decreasing throughout the collecting period the axial length of successively formed helices.

2. A method for the preparation of heavy packages of freshly spun rayon thread which comprises, supplying for collection thread moving at a substantially uniform linear speed, forming such thread as supplied into a plurality of superimposed oppositely directed substantially true helices, traversing the thread across the face of the said package at a constant speed between reversals of direction at any given time and from a point in contact with the surface of the package, and continuously decreasing throughout the collecting period the axial length of successively formed helices at a rate in direct proportion to the rate of formation thereof.

3. In apparatus for the bobbin spinning of rayon including, a thread source, a driven thread package collecting bobbin and a traverse member, means for continuously producing reciprocating motion of unvarying characteristics, a connecting means for imparting unimpaired the motion produced by said first means to the traverse member, means for continuously reducing at a directly proportional ratio the stroke amplitude of the traverse member and the speed of travel thereof between changes in direction, and a package contacting thread guide carried by said traverse member and movable axially of the bobbin to direct laying up of thread thereon.

4. In apparatus for the bobbin spinning of rayon including, a thread source, a driven thread package collecting bobbin and a traverse member, means for continuously producing reciprocating motion of unvarying characteristics, a connecting means for imparting unimpaired the motion produced by said first means to the traverse member, means constituting a part of said connecting means for continuously reducing at a

directly proportional ratio the stroke amplitude of the traverse member and the speed of travel thereof between changes in direction, and a package contacting thread guide carried by said traverse member and movable axially of the bobbin to direct laying up of thread thereon.

5. In apparatus for the bobbin spinning of rayon, including, a thread source, a driven thread package collecting bobbin and a traverse member, a cam for continuously producing reciprocating motion of unvarying characteristics, connecting means for imparting unimpaired the motion of said cam to the traverse member, means constituting a part of said connecting means for continuously reducing at a directly proportional ratio the stroke amplitude of the traverse member and the speed of travel thereof between changes in direction, and a package contacting thread guide carried by said traverse member and movable axially of the bobbin to direct the laying up of thread thereon.

6. In apparatus for the bobbin spinning of rayon including, a thread source, a driven thread package collecting bobbin and a traverse member, a cam for continuously producing reciprocating motion of a linear speed directly proportional to the angular velocity of the cam, connecting means for imparting unimpaired the motion of said cam to the traverse member, means constituting a part of said connecting means for continuously reducing at a directly proportional ratio the stroke amplitude of the traverse member and the speed of travel thereof between changes in direction, and a package contacting thread guide carried by said traverse member and movable axially of the bobbin to direct the laying up of thread thereon.

7. In apparatus for the bobbin spinning of rayon including, a thread source, a thread package collecting bobbin and a traverse member, a cam for continuously producing reciprocating motion of a linear speed directly proportional to the angular velocity of the cam, connecting means for imparting unimpaired the motion of said cam to the traverse member, means constituting a part of said connecting means for continuously reducing at a directly proportional ratio the stroke amplitude of the traverse member and the speed of travel thereof between changes in direction, a package contacting thread guide carried by said traverse member and movable axially of the bobbin to direct the laying up of thread thereon, and means for driving said cam and bobbin in synchronism.

8. In apparatus for the bobbin spinning of rayon including, a thread source, a thread package collecting bobbin and a traverse member, a cam for continuously producing reciprocating motion of a linear speed directly proportional to the angular velocity of the cam, connecting means for imparting unimpaired the motion of said cam to the traverse member, means constituting a part of said connecting means for reducing at a directly proportional ratio the stroke amplitude of the traverse member and the speed of travel thereof between changes in direction, means for actuating said reducing means proportionally to the number of changes of direction of said connecting means, and a package contacting thread guide carried by said traverse member and movable axially of the bobbin to direct the laying up of thread thereon.

9. In apparatus for the bobbin spinning of rayon including, a thread source, a thread package collecting bobbin and a traverse member, a

cam for continuously producing reciprocating motion of a linear speed directly proportional to the angular velocity of the cam, connecting means for imparting unimpaired the motion of said cam to the traverse member, means constituting a part of said connecting means for reducing at a directly proportional ratio of the stroke amplitude of the traverse member and the speed of travel thereof between changes in direction, means for actuating said reducing means proportionally to the number of changes of direction of said connecting means, a package contacting thread guide carried by said traverse member and movable axially of the bobbin to direct the laying up of thread thereon, and means for driving said cam and bobbin in synchronism.

10. In apparatus for the bobbin spinning of freshly spun rayon thread including, a thread source, a foraminated thread package collecting bobbin and a traverse bar, a cam for continuously producing reciprocating motion of a linear speed directly proportional to the angular velocity of the cam, said cam having a peripheral groove therein, a follower in said groove, means for confining the movement of said follower to a single plane, a rod pivotally connected to said follower, the free end of said rod being pivotally attached to a nut, an arm including a screw receiving said nut, a rock shaft, said arm being attached to said rock shaft at a point substantially remote from the location of said screw, said rock shaft being driven through said arm by the rod connected to the cam follower, means carried by said arm for turning said screw to vary the distance of said nut from the rock shaft proportional to the number of reciprocating strokes thereof, a traverse bar driven from the rock shaft to which said arm is attached, a package contacting thread guide carried by said traverse bar, and means for driving said cam and bobbin in synchronism.

11. In apparatus for the bobbin spinning of freshly spun rayon including, a source of thread, a driven collecting bobbin and a reciprocating traverse bar operatively associated therewith, a package contacting thread guide comprising, a hub portion pivotally attached to the traverse bar at a point below but in the same vertical plane as the axis of the bobbin, a thread receiving portion extending upwardly from said hub to contact tangentially the cylindrical wall of said bobbin, and a counterweight depending downwardly from said hub in alignment with said thread receiving portion.

12. In apparatus for the bobbin spinning of freshly spun rayon including, a source of thread, a driven collecting bobbin and a reciprocating traverse bar operatively associated therewith, a package contacting thread guide comprising, a hub portion pivotally attached to the traverse bar at a point below but in the same vertical plane as the axis of the bobbin, a bifurcated portion extending upwardly from said hub to contact tangentially the cylindrical wall of said bobbin, and a counterweight depending downwardly from said hub in alignment with said bifurcated portion, whereby the bifurcated portion will always contact the bobbin or the package wound thereon to insure the laying up of thread exactly in accordance with the pattern of movement of the traverse bar.

13. In apparatus for the bobbin spinning of rayon including a thread source, a driven thread package collecting bobbin and a traverse member, means for continuously producing reciprocating motion of unvarying characteristics, a connecting

means for transmitting to the traverse member substantially unimpaired the motion produced by said first means and a package contacting thread guide carried by said traverse member and movable axially of the bobbin to direct laying up of thread thereon.

14. In apparatus for the bobbin spinning of rayon including, a thread source, a driven thread package collecting bobbin and a traverse member, means for continuously producing reciprocating motion of unvarying characteristics, a connecting means for transmitting to the traverse member substantially unimpaired the motion produced by said first means, means acting on said connecting means for reducing the stroke amplitude of the traverse member without altering the reciprocating motion of unvarying characteristics, and a package contacting thread guide carried by said traverse member and movable axially of the bobbin to direct laying up of thread thereon.

15. In apparatus for the bobbin spinning of rayon including a thread source, a driven thread package collecting bobbin and a traverse member, means for continuously producing reciprocating motion of unvarying characteristics, a connecting means for transmitting to the traverse member substantially unimpaired the motion produced by said first means, means for progressively reducing the stroke amplitude of the traverse member during the collection period, the speed of travel of the traverse member between changes in direction varying directly with the speed of the means for continuously producing reciprocating motion and as a function of the stroke amplitude, and a package contacting thread guide carried by said traverse member and movable axially of the bobbin to direct laying up of the thread thereon.

ARTHUR L. JACKSON.
